UNITED STATES PATENT OFFICE.

AUGUST ASSMANN, OF NEW YORK, N. Y.

DESIGN FOR A PICTURE-FRAME.

SPECIFICATION forming part of Design No. 35,021, dated September 3, 1901.

Application filed July 26, 1901. Serial No. 69,859. Term of patent 14 years.

To all whom it may concern:

Be it known that I, AUGUST ASSMANN, a citizen of Germany, residing at New York, in the county of New York and State of New York, have invented and produced a new and original Design for Picture-Frames, of which the following is a specification, reference being had to the accompanying drawings, forming part thereof.

10 Figure 1 is a plan view of my newly-designed picture-frame; Fig. 2, a side view looking in the direction of the arrow 2 of Fig. 1; Fig. 3, an end view looking in the direction of the arrow 3 of Fig. 1, and Fig. 4 an end view 15 looking in the direction of the arrow 4 of Fig. 1.

My newly-designed picture-frame is rectangular in form, and the leading or material feature thereof consists of a series of similar 20 triangular longitudinal raised portions *a* at each side, a central triangular raised portion *b* at each side, and depressed irregularly-formed portions *c* at each side and between the raised portions, the side portions of all of 25 said portions being stepped and provided with notches or recesses. One end of the frame is also provided with a plurality of tri-

angular depressed longitudinal portions *d*, between which is a depressed triangular portion *e*, each of said portions being stepped in form 30 and the side walls thereof being provided with notches or recesses, while the other end of said frame comprises central longitudinal triangular raised portions *g* at each end and at the sides thereof irregularly-formed depressed 35 portions *h*, between which are central raised portions *g*, all of said portions being stepped and provided with notches or recesses. The parts of the frame are also differently colored, as shown in Fig. 1.

Having fully described my invention, what I claim as new, and desire to secure by Letters Patent, is—

The design for a picture-frame, herein shown and described.

In testimony that I claim the foregoing as my invention I have signed my name, in presence of the subscribing witnesses, this 22d day of July, 1901.

AUGUST ASSMANN.
